IGNITION SYSTEM

Edward F. Wargin, San Anselmo, Calif., and Joseph R. Harkness and Donald C. Peroutky, Schenectady, N. Y., assignors to General Electric Company, a corporation of New York

Application February 27, 1947, Serial No. 731,230

13 Claims. (Cl. 315—218)

1

This invention relates to ignition systems for internal combustion engines and more particularly to ignition systems of the type wherein the electrical power is supplied by a magneto generator.

Magneto generators of the type now in general use are provided with breaker switch mechanisms which periodically open and close the magneto primary coil circuit. This action of the breaker switch causes a high rate of change of magnetic flux threading the magneto coil which results in a high induced voltage in the coil necessary to fire the spark plugs, which action is particularly important at low operating speeds when the rate of magnetic flux change due to the generator action alone is relatively slow. These breaker mechanisms are difficult to adjust for proper timing and are a source of much ignition trouble. It has long been realized that it would be highly advantageous to eliminate the breaker mechanism and simply rely on the magnetic flux change inherent in the operation of the magneto generator to produce the necessary voltage in the magneto coil. Previous attempts to do this, however, have not been very successful because of the fact that a breakerless magneto generator inherently produces a voltage which varies approximately with the magneto speed. Because of this fact, the required operating voltage at low engine speed could not be obtained without paying a prohibitive penalty in terms of weight of magnetic material or number of magneto coil turns required. For this reason breakerless magneto systems have not heretofore been able to compete favorably with the conventional breaker type.

An object of the present invention is to provide a new and improved ignition system for internal combustion engines.

Another object is to provide an improved ignition system which is well adapted for use with a breakerless type of magneto and which will provide the required operating voltage at low operating speed without requiring the magneto generator to be of excessive size or weight.

A further object is to provide an improved ignition system which is simple in construction, light in weight, easy to service and maintain, and which is easily adapted to many applications without major design changes.

Further objects and advantages of our invention will become better understood from the following description referring to the accompanying drawing, and the features of novelty which characterize our invention will be pointed out

with particularity in the claims annexed to and forming a part of the specification.

In the drawing Fig. 1 illustrates somewhat diagrammatically an ignition system embodying the present invention which is arranged, for exemplary purposes, to provide single ignition for an internal combustion engine having 28 cylinders.

Fig. 2 of the drawing illustrates how the system of Fig. 1 can be modified by a simple change to provide dual ignition for an engine having 14 cylinders. Fig. 2 of the drawing also illustrates the position of the magneto generator rotor after it has rotated counterclockwise an angular distance equal to the width of a stator tooth from the position shown in Fig. 1.

Referring now to the drawing there is shown an ignition system of the low tension, high frequency type wherein the electrical power is supplied by a magneto generator of the breakerless type indicated generally at 1. The magneto generator 1 is of the so-called inductor type and comprises a rotary member 2 mounted on a drive shaft 3. The rotor 2 is formed of magnetic material and is preferably of laminated construction, the rotor being provided with a plurality of circumferentially-spaced, salient teeth 4. Extending around the rotor member 2 is a stator member comprising four, spaced, arcuate pole pieces 5, 6, 7 and 8 which are formed of magnetic material and which are preferably of laminated construction. Each stator pole piece is provided with a plurality of inwardly extending projections or teeth 9 which cooperate with the rotor teeth 4 in establishing different low reluctance magnetic circuit paths through the rotor and the stator pole pieces as will be subsequently further described.

The magneto 1 is provided with two output coils 10 and 11 which are carried, respectively, on the magnetic core members 12 and 13. As illustrated in the drawing, the core member 12 is arranged magnetically to interconnect the stator pole pieces 5 and 6 while the core member 13 is arranged magnetically to interconnect the stator pole pieces 7 and 8, the core members 12 and 13 being located on diametrically opposite sides of the magneto stator.

For the purpose of providing a source of magnetic flux which is periodically directed through the core members 12 and 13 in opposite directions upon rotation of the rotor member 2, there are provided two permanent magnets 14 and 15 located on diametrically opposite sides of the stator. As shown the permanent magnet 14 is arranged so that its polar extremities abut the ad-

jacent ends of the stator pole pieces 5 and 8 and thereby forms a magnetic link between the two pole pieces. Also as shown the permanent magnet 15 is similarly arranged with its polar extremities abutting the adjacent ends of the stator pole pieces 6 and 7. This magnet also acts as a magnetic link interconnecting these two pole pieces.

When the rotor 2 of the magneto rotates the magnetic flux of the permanent magnets 14 and 15 is caused first to pass through the core members 12 and 13 in one direction and then to be rapidly changed or switched so as to flow through the core members in the reverse direction, this alternate and rapid flux switching causing high induced voltages in the magneto output coils 10 and 11. This flux switching action of the magneto generator may more easily be understood by a consideration of the low reluctance magnetic flux paths when the generator rotor is in each of two different positions indicated respectively in Figs. 1 and 2 of the drawing. When the rotor 2 is in the position indicated in Fig. 1 of the drawing, the rotor teeth 4 lie opposite the stator teeth of pole pieces 6 and 8 so that a low reluctance path is established interconnecting these two pole pieces diametrically across the rotor. At this time the rotor teeth and the inwardly extending teeth of pole pieces 5 and 7 are out of registration so that the flux path between these two pole pieces extending diametrically across the rotor is of relatively high reluctance. With the rotor of the generator in the position shown in Fig. 1, two low reluctance magnetic circuit paths are established, one of which may be traced as follows: The north pole of magnet 14, stator pole piece 5, core member 12, stator pole piece 6, diametrically across rotor 2, pole piece 8 and back to the south pole of magnet 14. The other path established may be traced as follows: North pole of magnet 15, stator pole piece 6, diametrically across rotor member 2, stator pole piece 8, core member 13, and stator pole piece 7 and back to the south pole of permanent magnet 15.

When the rotor member 2 of the magneto generator rotates counterclockwise an angular amount equal to the width of a stator tooth from the position shown in Fig. 1, it occupies the position shown in Fig. 2. Referring to Fig. 2, it will be noted that the rotor member 2 now establishes a low reluctance magnetic circuit path extending diametrically across rotor 2 between the pole pieces 5 and 7. At this time the rotor teeth 4, lying opposite the stator pole pieces 6 and 8, are out of registration with the stator teeth 9 so that the reluctance of the magnetic circuit path extending diametrically across the rotor between the stator pole pieces 6 and 8 is relatively high. With the magneto rotor in the position shown in Fig. 2 it will be noted that there are now two low reluctance magnetic paths whereby the magnetic flux of the permanent magnets 14 and 15 threads the core members 12 and 13 in the opposite direction from that shown in Fig. 1. One of these magnetic circuit paths may be traced as follows: The north pole of permanent magnet 14, stator pole piece 5, diametrically across rotor member 2, stator pole piece 7, core member 13, and stator pole piece 8 back to the south pole of permanent magnet 14. The other path may be traced as follows: The north pole of magnet 15, stator pole piece 6, core member 12, stator pole piece 5, diametrically across rotor member 2, the stator pole piece 7 back to the south pole of permanent magnet 15.

In view of the above described explanation, it is believed that it will now be clear that as the rotor member 2 rotates, the magnetic flux of the permanent magnets 14 and 15 is alternately switched through the core members 12 and 13 in opposite directions to cause induced voltages in the coils 10 and 11 of alternating polarity. In order that the voltages induced in the magneto coils 10 and 11 may be as high as possible, the magneto rotor and stator teeth are so designed as to cause a very rapid change in the magnetic flux threading the core members 11 and 12, while the generator rotor member 2 is rotating between the positions shown in Figs. 1 and 2 of the drawing. In order to accomplish this the stator teeth 9 are, as shown, made very narrow so that their width is appreciably less than the width of the rotor teeth 4. While the expedient of making the stator teeth 9 narrow is desirable from the standpoint of obtaining a rapid flux change, it has the disadvantage that it reduces the cross-sectional area of the stator tooth for an axial length of the tooth of any given value. The amount of magnetic energy required to be stored in the magnetic circuit of the magneto for each impulse determines the cross-sectional area of the stator teeth and therefore in the conventional single-tooth stator construction this results in unduly long stator teeth which is undesirable from the size standpoint. In the present arrangement this difficulty is obviated by utilizing a plurality of parallel stator teeth on each pole piece so as to provide a plurality of parallel flux paths. Thus it will be noted that in the illustrated arrangement each of the stator pole pieces 5, 6, 7 and 8 is provided with four inwardly extending stator teeth 9. This arrangement permits the required amount of pole piece cross-sectional area to conduct the required amount of magnetic flux without necessitating an undesirably long stator tooth. Obviously more or less than four stator teeth per pole piece can be used, depending upon the design considerations involved.

While the use of narrow stator teeth in the magneto generator described above results in a very considerable increase in the voltage output of the coils 10 and 11, the output voltage still varies as a function of rotor speed which is disadvantageous as pointed out above where it is desired to eliminate the breaker mechanism and still obtain sufficient voltage to fire spark plugs at the minimum required operating speed. In order to overcome this difficulty without the need for utilizing an excessively large magnetic structure and without using an excessively large number of turns of wire in the magneto output coil, there is provided in accordance with this invention an arrangement whereby energy from successive impulses of the magneto may be stored in a plurality of series connected condensers which are arranged to be periodically discharged through a distributor in a series additive manner.

Referring now to the details of the ignition distribution arrangement, and more particularly to the distribution arrangement associated with the magneto output coil 10, it will be noted that there is provided a pair of series connected storage condensers 16 and 17 having a common terminal 18 which is connected to one of the output leads 19 of magneto coil 10. The remaining terminal 20 of the condenser 16 is connected to the other coil lead 21 through a half-wave rectifier 22 as shown. The remaining terminal 23 of the condenser 17 is also connected to the coil lead 21 through a parallel circuit including

another half-wave rectifier 24. The magnetic and electrical polarities are so selected in connection with the current conducting directions of the rectifiers 22 and 24 such that when the output of coil 10 is of one polarity, one of the condensers, say condenser 16, is charged in the direction indicated, for example, by the polarity marks on the drawing. Due to the action of the rectifiers 22 and 24, the next succeeding voltage impulse of opposite polarity from the coil 10 causes the condenser 17 to be charged with the polarity as indicated on the drawing while the charge in the condenser 16 is held. It will be noted that the polarities of the condensers 16 and 17 when charged are such that they are series aiding or additive, that is, the voltage across the terminals 20 and 23 when the condensers are fully charged is substantially greater than across either condenser alone and may be approximately twice as great for the illustrated case where two condensers are used. In order to utilize this voltage cascading arrangement advantageously, a circuit arrangement is provided whereby the voltage across the terminals 20 and 23 is periodically applied by a distributor to various ignition circuits to fire spark plugs associated therewith. To this end the terminal 20 is grounded as indicated and the terminal 23 is connected through the lead 25 to a rotary distributor indicated generally at 26. The distributor 26 is shown as comprising a plurality of stationary electrodes 27 which are arranged in a circular pattern. Cooperating with the stationary electrodes 27 is a rotary electrode or distributor finger 28 which may be conveniently mounted on shaft 3 as shown, so as to be rotated in synchronism with the rotor member 2 of the magneto generator. The lead 25 is connected to the distributor finger 28 through a slip ring arrangement 29 of conventional construction.

The ignition circuits illustrated are of the so-called low tension, high frequency type. For the purpose of simplicity, only one such circuit is illustrated in the drawing as associated with each distributor but it will be understood that in actual practice there will be a separate ignition circuit and associated spark plug connected to each of the distributor electrodes.

The ignition circuit shown in connection with distributor 26 comprises a step-up transformer 30 having a primary or low voltage winding 31 and a secondary or high voltage winding 32. The secondary winding 32 of the step-up transformer is connected to energize a spark plug 33 while the primary winding 31 is arranged to be periodically connected by the distributor 26 to be energized by the series-connected condensers 16 and 17. In ignition systems of this type a spark gap is used to initiate a high-frequency oscillatory discharge in the primary circuit of the step-up transformer 30 and in the illustrated arrangement the distributor used is a so-called air-gap type so that the required spark discharge takes place between the rotary distributor finger 28 and associated electrodes. Thus as the distributor finger 28 rotates it approaches to within arcing distance of the electrodes 27 but does not actually contact the electrodes. An advantage of this type of ignition circuit lies in the fact that the distributor voltage may be of relatively low magnitude, for example, on the order of 3 kilovolts while the high voltage applied to the spark plug 33 which, for example, may be of the order of 18 kilovolts, is confined to the spark plug and the secondary winding of the step-up trans-

former 30. In order to eliminate corona loss to the surrounding atmosphere and step-up transformer 30 may be advantageously hermetically sealed in the spark plug, as will be well understood by those skilled in the art.

In ignition systems designed for radial engines there must be provided compensation for timing irregularities which occur due to the use of articulated piston rods. In conventional ignition systems of the breaker type this compensation is usually provided by properly selecting the angular relation of the cam lobes used to operate the breaker switch. In the present breakerless system some other method must be used. Such timing compensation can be conveniently obtained in the present system by an appropriate circumferential spacing of the distributor electrodes. The non-symmetrical spacing of the electrodes provided for such compensation is, however, a relatively slight departure from a symmetrical arrangement and does not appreciably affect the two-pulse charging cycle of the series connected storage condensers.

In order to provide positive on-off control of the magneto, a small primary winding (not shown) may be provided on each of the core members 12 and 13. With such an arrangement the magneto can be rendered inactive in a positive manner by simply providing a suitable switching arrangement to short the primary windings to prevent rapid fluctuations of the core flux.

The construction of the magneto generator is such that it lends itself advantageously to the dual ignition arrangement illustrated wherein separate distribution circuits are associated with each of the two output coils 10 and 11, the distribution circuit associated with the output coil 10 having been described above. In order to utilize advantageously the output of the secondary magneto coil 11, there is provided another ignition distribution system which may be, as shown, the same as that already described in connection with the magneto output coil 10. Parts of the second distribution system corresponding to those already described have been given the corresponding reference numerals except that the numerals have been primed in order to differentiate between the systems. As will be more fully described the dual distribution arrangement has the advantage that by initially adjusting the position of the distributor fingers 28 and 28' the same apparatus may be used to provide dual ignition for an engine having n cylinders or single ignition for an engine having $2n$ cylinders.

In order to clarify the description of operation of our improved ignition system by a concrete example, there is illustrated a system which, when adjusted as shown in Fig. 1, will provide single ignition for an internal combustion engine having 28 cylinders and when adjusted as shown in Fig. 2 will provide dual ignition for an engine having 14 cylinders. In the system illustrated the rotor 2 of the magneto generator is provided with 14 rotor teeth and each of the distributors is provided with 14 stationary electrodes, making a total of 28 which are connected to 28 separate ignition circuits. With this arrangement the shaft 3 which drives the magneto generator rotor and the distributor fingers 28 and 28' may be conveniently connected to the internal combustion engine so as to operate at one-half engine crankshaft speed. The characteristic of the magneto generator 1 is such that it inherently

produces a number of impulses of alternating polarity in each of the coils 10 and 11 equal to twice the number of rotor teeth for each revolution of the rotor shaft. Thus in the illustrated arrangement there will be 28 voltage impulses of alternate polarity induced in each of the coils 10 and 11 for each revolution of the drive shaft 3. Assuming the electrodes 27 and 27' to be approximately equally spaced it will also be clear that the magneto generator will produce two voltage impulses in the time interval required for each distributor finger to move from a position opposite one electrode to a position opposite the next adjacent electrode. By properly selecting the angular positions of the distributor fingers 28 and 28' on the drive shaft 3, the magneto generator is made to deliver two impulses per charging cycle to each pair of storage condensers 16, 17 and 16', and 17'. With this timing arrangement the series-connected storage condensers are ready for discharge through an ignition circuit each time a distributor finger moves opposite a stationary electrode.

In the arrangement shown in Fig. 1 the distributor fingers 28 and 28' are staggered, as shown, so that when the finger 28' is opposite an electrode 27' in distributor 26', the distributor finger 28 of the distributor 26 lies approximately midway between two of the electrodes 27. With this arrangement it will be clear that all the 28 ignition circuits energized from the distributors will be fired in sequence so that the system may be utilized to provide the single ignition for an engine having 28 cylinders. With the illustrated arrangement if it is desired to provide instead dual ignition for an engine having 14 cylinders this can be accomplished by a simple adjustment of either of the distributor fingers on the drive shaft 3. For example, to accomplish this an arrangement is shown in Fig. 2 wherein both distributor fingers 28 and 28' are so oriented on the drive shaft 3 that they arrive opposite stationary electrodes at the same time. With this arrangement it will be clear that the 28 ignition circuits will be periodically and sequentially fired in pairs so that the system can be utilized to provide dual ignition for an engine having 14 cylinders. Thus in Fig. 2 both of the spark plugs 32 and 32' are indicated as being arranged to fire a single cylinder 34.

In addition to the flexibility afforded by the dual distribution arrangement described above, the breakerless ignition system disclosed herein has other marked advantages of equal or greater importance. Thus due to the fact that the series connected condensers, such as 16 and 17, produce an additive discharge voltage which is considerably larger than the voltage of each magneto impulse, adequate operating voltage is obtained at minimum operating speed without using the conventional breaker mechanism or without using a magneto generator which is undesirably large. Stated in another way, the ignition circuit of this invention makes possible the use of a breakerless type of magneto wherein the magneto generator is no larger, and in some cases is smaller, than the magneto now used with a breaker type of system.

Another advantage of the voltage-multiplying arrangement of the series-connected condensers is the fact that the output voltage of the magneto coils needs only to be a fractional part of the distributor voltage which results in a substantial saving in the insulation requirements for the coil.

A still further advantage of the present system

is that it permits a greatly simplified mechanical and electrical construction. Thus the magneto rotor and the distributor fingers may be mounted on a common-drive shaft so that the apparatus has only one moving part and, of course, the conventional trouble-making breaker mechanism is completely eliminated without sacrificing weight or operating speed range. Since more than one magneto impulse is used per spark discharge, it is possible to drive the magneto rotor and distributors at one-half engine crankshaft speed regardless of whether the engine has an even or odd number of cylinders.

Advantages arising from the use of series condensers connected in additive or aiding relation which are sequentially charged by consecutive magneto impulses are obtained regardless of whether or not the condensers are of the same size. However, we have found, as a result of extensive tests, that improved results can be obtained if the capacities of the condensers of each set are selected in the ratio of approximately 4 to 1, the condensers being so arranged that the condenser first to be charged in each charging cycle has the larger capacity. With this arrangement the first condenser is charged to a lower voltage so there is less leakage loss through the rectifier while the second condenser is being charged. Also the second condenser charges more rapidly so that a full charge is insured before the distributor finger arrives within arcing distance of the electrode through which the subsequent discharge takes place.

It should be clearly understood that the present invention is not limited to the illustrated arrangement wherein two series condensers are sequentially charged in a two-impulse charging cycle. Obviously more impulses per charging cycle may be used if desired without departing from our invention. The system can, of course, be designed for engines having any number of cylinders by proper correlation of the number of magneto impulses per revolution with the number of distributor electrodes. The only limitation is that where the number of engine cylinders is odd, the number of charging impulses per charging cycle must be even in order to obtain the advantage of driving the distributor and magneto rotor at the same speed. The reason for this is the fact that the magneto inherently produces an even number of impulses per revolution.

While our invention is well adapted for use with an ignition system of the low-tension, high-frequency type, its use is not necessarily limited thereto. Thus for some applications the electrodes of the distributor may be connected directly to the spark plugs, thereby eliminating the spark plug transformer. In such case a contact type of distributor may be used.

We do not claim broadly in this patent an arrangement wherein two or more magneto impulses are used cumulatively to charge condenser storage means prior to discharge, as this subject matter is claimed in a copending application Serial No. 728,870, filed in the names of Edward F. Wargin and Arthur W. Robinson, Jr., which application is assigned to the same assignee as the present invention. We do, however, claim the illustrated arrangement wherein the condenser storage means is in the form of a plurality of separate condensers connected in series additive relation.

Although we have shown and described particular embodiments of our invention, we do not desire to be limited to the particular embodiment

ments described, and we intend in the appended claims to cover all modifications which do not depart from the spirit and scope of our invention.

What we claim as new and desire to secure by Letters Patent of the United States is:

1. In an ignition system, a generator for producing periodic voltage impulses, voltage doubler type circuit means including a plurality of condensers connected series aiding, whereby a voltage impulse from said generator charges one of said condensers and a later voltage impulse from said generator charges another of said condensers, and discharging means arranged to simultaneously discharge said series connected condensers through ignition apparatus, said generator and said discharging means being synchronized and correlated so that each of said condensers receives a charging impulse from said generator prior to discharge through said ignition apparatus.

2. In an ignition system, a generator for producing voltage impulses of alternating polarity, a plurality of condensers connected series aiding, circuit means including rectifiers interconnecting said condensers and said generator in such a manner that a voltage impulse from said generator of one polarity charges one of said condensers and the voltage impulse of the opposite polarity charges another of said condensers, means for connecting said condensers in series so that the charges thereon are additive, and a distributor arranged to simultaneously discharge said series connected condensers, said generator and said distributor being synchronized and correlated so that each of said condensers receives a charging impulse from said generator prior to said discharge by said distributor.

3. An ignition system adapted to be energized from a magneto generator of the type which produces successive voltage impulses comprising a plurality of condensers connected series aiding, rectifier means connecting said condensers to be sequentially charged by successive voltage impulses from said generator, and a distributor arranged to simultaneously discharge said series connected condensers through ignition apparatus, said generator and said distributor being synchronized and correlated so that each of said condensers receives a charging impulse from said generator prior to discharge through said distributor.

4. An ignition system comprising a magneto having a rotatable member and an output coil which produces successive voltage impulses upon rotation of said rotatable member, a pair of condensers connected series aiding, selective charging circuit means connecting said condensers to said coil so that a voltage impulse charges one of said condensers and a subsequent impulse charges another of said condensers while the charge on said first condenser is maintained, and a distributor arranged to simultaneously discharge said series connected condensers through ignition apparatus, said rotatable member in said distributor being synchronized and correlated so that each of said condensers receives a charging impulse from said output coil prior to discharge through said distributor.

5. An ignition system comprising a magneto having a rotatable member and an output coil which produces successive voltage impulses of alternating polarity upon rotation of said rotatable member, a pair of condensers connected series aiding, circuit means including rectifiers for connecting said condensers to said coil so that

a voltage impulse of one polarity charges one of said condensers and a voltage impulse of the opposite polarity charges the other of said condensers, and a distributor arranged to simultane-

5 ously discharge said series connected condensers through ignition apparatus, said rotatable member and said distributor being synchronized and correlated so that each of said condensers receives a charging impulse from said output coil
10 prior to said discharge through said distributor.

6. An ignition system adapted to be energized

15 by a magneto generator having an output coil in which voltages of alternating polarity are induced, a pair of series connected condensers having a common connection, means for connecting said common connection to one terminal of said output coil, circuit means providing two parallel paths connecting the other condenser connections to the other terminal of said output coil, each of said parallel paths including a rectifier.

20 coil, each of said parallel paths including a rectifier so connected that consecutive magnetic coil

25 her so connected that consecutive magnetic coil voltage impulses of opposite polarity cause first one condenser to charge and then the other, and a distributor arranged to simultaneously discharge the voltage across said series connected condensers through ignition apparatus comprising spark plug means, said generator and said distributor being synchronized and correlated so that each of said condensers receives a charging impulse from said output coil prior to discharge through said distributor.

7. An ignition system adapted to be energized

38 by a magneto generator having an output coil in which voltages of alternating polarity are induced, a pair of series connected condensers having a common connection, circuit means for connecting said common connection to one ter-

40 minal of said output coil, circuit means providing two parallel paths connecting the other condenser connections to the other terminal of said output coil, each of said parallel paths including a rectifier so connected that consecutive magnetoo coil voltage impulses of opposite polarity cause

45 first one condenser to charge and then the other, said condensers having different capacities being arranged so that the condenser having the greater capacity is the first to charge, and a distributor synchronized with said generator and arranged

50 to simultaneously discharge the voltage across said two series connected condensers through ignition apparatus to cause firing of spark plug means associated therewith, said discharge occurring only after each of said condensers has received charging impulse from said output coil.

55 8. An ignition system comprising a breakerless magneto of the inductor type having an output coil in which voltages of alternating polarity are induced, a pair of series connected condensers, circuit means including rectifiers interconnecting said condensers and said output coil in such a manner that positive voltage is applied to the primary of the output coil during the time the condensers are being charged.

60

65 manner that consecutive output coil voltages of alternating polarity cause sequential charging of said condensers whereby the voltage across said series connected condensers when charged is greater than the voltage induced in said output coil during each voltage impulse thereof, and a rotary distributor mechanically synchronized with said generator arranged to periodically discharge said series connected condenser after each of said condensers has received a charging impulse from

70 said output coil.

9. An ignition system comprising a breaker-
less magneto of the inductor type having an out-
put coil in which voltages of alternating polarity
are induced, a pair of series connected condensers,
75 circuit means including rectifiers interconnecting

said condensers and said output coil in such a manner that consecutive output-coil voltages of alternating polarity cause sequential charging of said condensers, and a rotary distributor of the gap type mechanically synchronized with said generator to periodically discharge said series connected condensers after charging thereof through an ignition circuit to cause the high frequency oscillatory discharge therein, a step-up transformer having a primary winding connected to be energized by said ignition circuit and a secondary winding, and a spark plug having electrodes connected to be energized from the secondary winding of said step-up transformer.

10. An ignition system comprising a magneto having a rotatable member and two output coils in which successive voltage impulses are induced upon rotation of said rotatable member, a first circuit means of the voltage doubling type including a pair of condensers connected to one of said coils so as to be sequentially charged by successive voltage impulses from said coil, a second circuit means of the voltage doubling type including a pair of condensers connected to the other of said coils so as to be sequentially charged by successive voltage impulses from said other coil, a pair of distributors each of which comprises a set of stationary electrodes and a cooperating rotatable finger member, means for rotating the finger members of said distributors and said magneto rotatable member at a predetermined relative speed, the spacing between successive electrodes of each of said distributors being such that at least two voltage impulses are induced in the associated magneto coil during the time interval required for a distributor finger to move from a position opposite one electrode to a position opposite an adjacent electrode, means for connecting each pair of condensers respectively to a rotating finger of one of said distributors, and an ignition circuit associated with each distributor electrode whereby all of the ignition circuits may be periodically energized by discharge from said condensers in sequence or two at a time depending on whether said distributor fingers are initially set in staggered or synchronized relation.

11. An ignition system comprising a magneto having a rotatable member and two output coils in which successive impulse voltages are induced upon rotation of said rotatable member, a first circuit means of the voltage doubling type including a condenser means connected to one of said coils so as to be cumulatively charged by successive voltage impulses from the coil, a second circuit means of the voltage doubling type including a condenser means connected to the other of said coils so as to be cumulatively charged by successive voltage impulses from said other coil, a pair of distributors each of which comprises a set of stationary electrodes and a cooperating rotatable finger member, means for rotating the

5 finger members of said distributors and said magneto rotatable member at a predetermined relative speed, the spacing between said successive electrodes of each of said distributors being such that at least two voltage impulses are induced in each magneto coil during the time interval required for an associated distributor finger to move from the position opposite one electrode to a position opposite an adjacent electrode, 10 means for connecting said first and second condenser means respectively to the rotating fingers of said distributors, and ignition circuits connected to the electrodes of said distributors whereby all of the ignition circuits may be periodically energized from said condenser means in sequence or two at a time depending on whether said distributor fingers are initially set in staggered or synchronized relation.

12. In combination, an alternating voltage generator, circuit means of the voltage doubling type coupled to said generator and receiving alternating voltage therefrom, said circuit means including condenser means charged to a direct voltage greater than the amplitude of said alternating voltage, and discharging circuit means synchronized with said generator for discharging said condenser means at periodic intervals at least as great as two half-cycles of said alternating voltage.

13. In an ignition system, a generator for producing voltage impulses of alternating polarity, a plurality of condensers connected series aiding, charging circuit means including rectifier means connected between said generator and said condensers for charging one of said condensers upon the production of a voltage impulse of one polarity and for charging another of said condensers upon the production of a voltage impulse of another polarity, a distributor arranged to simultaneously discharge said series connected condensers, and synchronizing means for said generator and distributor, said last-mentioned means driving said distributor at a rate to discharge said condensers after each has received at least one charging impulse from said generator.
